DESIGN FOR A TOY

Alfred Herz, New York, N. Y.

Application March 16, 1939, Serial No. 83,595

Term of patent 3½ years

To all whom it may concern:

Be it known that I, Alfred Herz, a citizen of Germany and a resident of the city of New York, Borough of Manhattan, county and State of New York, have invented the new, original, and ornamental Design for a Toy, of which the following is a specification, reference being had to the accompanying drawing, forming part thereof, in which—

Fig. 1 is a side elevational view of a toy showing my new design. The appearance of the opposite side of the toy is similar to that of the side shown.

Fig. 2 is a top plan view of the toy, the cord and ring illustrated in dotted lines in Fig. 1 being omitted.

The dominant feature of the design resides in the profile of a human head having an elongated nose of the type shown.

I claim:

The ornamental design for a toy, as shown and described.

ALFRED HERZ.
